BY

Auguestine B. Stoeckton

ATTORNEY.

UNITED STATES PATENT OFFICE.

BRUCE FORD, OF PHILADELPHIA, PENNSYLVANIA.

VENT-COVER FOR STORAGE BATTERIES.

1,370,012.

Specification of Letters Patent.

Patented Mar. 1, 1921.

Application filed September 18, 1919. Serial No. 324,638.

To all whom it may concern:

Be it known that I, BRUCE FORD, a citizen of the United States, residing at Philadelphia, in the county of Philadelphia and 5 State of Pennsylvania, have invented a certain new and useful Vent-Cover for Storage Batteries, of which the following is a specification.

Storage battery jars, more especially those 10 in use on submarines, are provided with openings used for filling and for the ingress of air for ventilation, and these openings are or should be provided with detachable covers adapted to permit of the free ingress 15 of air and to exclude foreign articles and removable for the purpose of filling or refilling the jars.

The principal object of the present invention is to provide a vent cover of a form 20 and construction which can be made of hard rubber or rubber material which presents limitations as to the form in which it can be manufactured, and of a form and construction which permits of the free access of air 25 and provides for all the other requirements of use.

The invention will be claimed at the end 30 hereof but will be first described in connection with the embodiment of it selected for illustration in the accompanying drawings forming part hereof and in which—

Figure 1, is a sectional view illustrating a vent cover embodying features of the invention in application to a cell cover of 35 which only parts are shown.

Fig. 2, is a plan view of the under side of the cover, and

Figs. 3 and 4, are sections taken on the lines 3—3, and 4—4 of Fig. 1.

40 In the drawings the vent cover, consisting of hard rubber or rubber material, comprises a dished disk or cap 1, internally provided with intersecting or cruciform ribs or radiating webs 2 and 3, having axial ex-

45 tensions 4 and 5, at the central portion of the disk, to form a guide, and some of the extensions are laterally provided with locking flanges 6, disposed toward the rim of the disk. As shown the locking flanges are 50 curved and are supported by walls 7 and 8, extending to the inner face of the disk.

Those skilled in the art of hard rubber manufacture will know that the described

form and structure can be successfully manufactured from hard rubber or rubber material, and it may be remarked that the cruciform shape of the rims affords free ingress, all around the rim, for air. In use the extensions 5 and 4, form a stem or guide for inserting the vent cover into the open end of the tube or stand pipe 9, of the vent fitting or ventilating tube, and the locking flanges 6, upon suitable rotary movement of the cover, engage grooves 10, in the interior of the tube 9, after the manner of a bayonet joint, and so prevent accidental detachment of the cover, while permitting of its ready removal. The ribs 2 and 3, constitute stops and seating on the end of the tube 9, support the cover. In fact by making the locking flanges 6, inclined, as shown in Fig. 4, they may serve to draw the ribs 2 and 3, up against the end of the tube 9.

I claim:

1. A vent cover for storage batteries comprising a dished disk internally provided with cruciform ribs having axial extensions at the central portion of the disk to form a guide and some of the extensions laterally provided with locking flanges disposed toward the rim of the disk.

2. A vent cover for storage batteries comprising a dished disk internally provided with cruciform ribs having axial extensions at the central portion of the disk to form a guide and some of the extensions laterally provided with curved locking flanges disposed toward the rim of the disk and equipped with supporting walls extending to the inner face of the disk.

3. A vent for storage batteries consisting of the combination of a ventilating tube, and a cap mounted over the end of the tube and provided with radiating webs having ventilation spaces between them and extending into the tube to center the cap, substantially as described.

4. A vent for storage batteries consisting of the combination of a ventilating tube, a cap covering the end of the tube and provided with radiating webs having ventilation spaces between them and of which portions extend into the tube and of which portions abut on the end of the tube and constitute stops.

BRUCE FORD.
